INVENTOR
Wm. F. Bossert
BY
Dennis Thompson
ATTORNEYS

UNITED STATES PATENT OFFICE.

WILLIAM F. BOSSERT, OF UTICA, NEW YORK.

SEMAPHORE.

Application filed June 7, 1921. Serial No. 475,750.

To all whom it may concern:

Be it known that I, WILLIAM F. BOSSERT, a citizen of the United States, residing at Utica, in the county of Oneida, in the State of New York, have invented new and useful Improvements in Semaphores, of which the following, taken in connection with the accompanying drawings, is a full, clear, and exact description.

- 10 This invention relates to certain improvements in semaphores, and more specifically to a new and improved semaphore blade connected to a semaphore spectacle in a new and improved manner.
- 15 A primary object of this invention is to provide a construction by which the semaphore blade can be securely fastened to the spectacle without the use of the usual blade grips, blade clasps, etc.
- 20 A further object is to produce a semaphore in which no part of the face of the blade need be hidden by clamps, grips or clasps, and which will give, therefore, a clear indication of the whole surface of the blade.
- 25 By the construction contemplated by me the blade is strengthened and is capable of giving a more perfect and clear indication and is readily and securely fastened to the spectacle.
- 30 Other objects and advantages relate to the details of form, construction and arrangement of the device, all as will more fully appear from the following description, taken in connection with the accompanying drawings, in which:

Figure 1 is an elevation of a structure embodying my invention.

Figure 2 is a plan view of the blade blank after the first operation has been performed.

40 Figure 3 is a view of the blank of Figure 2 after the second operation has been performed.

Figure 4 is a view of the blank of Figure 2 somewhat enlarged after the third operation has been performed.

Figure 5 is a view of the blank of Figure 1 somewhat enlarged after the fourth operation has been performed.

50 Figure 6 is a section on line 6-6', Figure 1.

Figure 7 is a section similar to the section of Figure —6— of a slightly modified form of structure.

Figure 8 illustrates the channel bar used to prevent the bolt heads from turning during the securement of the blade to the spectacle.

The invention consists particularly in the form and construction of the semaphore blade —1—, the blank for which is illustrated in Figure 2 after the first operation has been performed. This operation consists merely in cutting the blank from any suitable sheet of proper material, as for instance, sheet metal in substantially the form shown in Figure 2, with the pairs of bayonet slots —2— in the opposite flanges —3— and —4—.

The second operation consists in forming the two intermediate corrugations to extend preferably partially throughout the length of the blade and the side corrugations —6— which extend throughout the entire length of the blade.

The next operation consists in bending the laterally extending side flanges —3— and —4— at substantially right angles to the body of the blade as indicated in Figure 4. The next operation consists in bending a portion of the ends of these side flanges into substantial parallelism with the body of the blade so as to form a rectangular structure comprising the front wall —7—, the side walls —8— and the inwardly extending flanges —9— and —10— constituting an incomplete rear wall and forming means for securing the blade to the spectacle, as hereinafter described.

The spectacle, as illustrated in Figure 1, is of the usual form and construction, and is provided with edge flanges —11— which assist in strengthening the spectacle and form an additional support for the blade. This spectacle —12— is ordinarily provided with a series of glass-covered opening —13— to be utilized for night indications, and the entire spectacle is adapted to be oscillated by means of a shaft —14— actuated by any suitable connections from any predetermined point.

The blade described is assembled with the spectacle in various ways, two of which are indicated in Figures 6 and 7.

In Figure 6 the body of the blade is of sufficient width to fit within the flanges —11— upon the spectacle —12— and may, as shown, be spaced therefrom by a strip —15— of suitable material constituting a strengthening strip, or washer, the spectacle and the said strip —15— being provided with properly aligned openings for the passage of a series of bolts —16—, ordinarily four in number, such bolts adapted to pass through the spectacle, the strip —15— and the bayonet slots in the flanges —3— and —4— of the blade, as shown in Figure 5, the formation of said slots permitting the use of the blade with spectacles in which the formed openings vary somewhat in space distance.

The bolt heads may be spaced from the flanges —9— and —10— by means of additional washers —17— as shown, if desired, and in view of the inaccessibility of the bolt heads and their position at the rear of the body of the blade, a channel strip —18— is provided for the purpose of preventing the bolt heads from turning when the nuts are being placed upon the bolts. This strip is formed from the blank shown in Figure 8, and in the manner shown in Figure 8, so as to be of a width capable of just receiving the head of the bolt when the slots —19— are fitted over the bolts, preferably between the washer —17— and the bolt head. The heads fit tightly within the channel bar and are prevented from turning thereby. Preferably, the openings —19— are somewhat elongated so as to permit slight variations in the spaced distance of the bolts.

It will be noted that with this construction no clamps or clasps are required, and that the bolt heads are invisible from the front of the semaphore. The construction so produced is strong and durable, and is easily assembled and the parts are rigidly retained in relative position, and the entire blade constitutes a non-obstructed indicating surface.

In Figure 7 a slightly modified construction is shown in that the side wall —20— is of somewhat greater length than the side wall —21— so that the rear flange —22— will extend along the outside of the flange —11— upon the spectacle and along the rear of the body of the spectacle so as to permit the passage of the bolts —22— therethrough when the spectacle is of the same construction as indicated in Figure 6. The flange —21— is of substantially the same size as the flange —8— shown in the former figures, and is adapted to fit within the flange —11— and to be secured thereto by the bolt —24—. Suitable washers —25— may be provided for spacing the bolt head and nut

from the flanges upon the blade, if desired, as indicated in the drawings.

It will be observed that the center corrugations —5— extend a considerable distance beyond the termination of the spectacle when the spectacle and blade are assembled in order to produce a comparatively rigid blade and give the structure the stiffness required. The side flanges, which extend throughout the entire length of the blade add to and increase this rigidity.

The blade —25— is perhaps preferably formed of thin sheet metal, such as steel and is coated with a vitreous enamel which preserves the metal and provides a color which is not readily effaced by exposure to the weather. However, it will be understood that although I have shown and described a specific construction as illustrative of perhaps preferred embodiments of my invention, I do not desire to limit myself to the details of form, construction or arrangement here disclosed, as various changes and modifications may be made in each of the same without departing from the invention as set forth in the appended claims.

I claim:

1. A semaphore comprising a spectacle, an enameled sheet metal blade with one or more center corrugations extending some distance beyond the spectacle, and two side corrugations along the outer edges of the blades and extending substantially the entire length of the blade to stiffen the same.

2. A semaphore comprising a spectacle, an enameled sheet metal blade with one or more center corrugations extending some distance beyond the spectacle, two side corrugations along the outer edges of the blades and extending substantially the entire length of the blade to stiffen the same, and laterally extending flanges at one end of the blade, said flanges provided with slots and bolts passed through said slots and through the spectacle.

3. In a semaphore, a blade provided with laterally extending flanges at one end, said flanges provided with bayonet slots for receiving bolts.

4. In a semaphore, a blade provided with laterally extending flanges at one end, said flanges provided with bayonet slots for receiving bolts, the inner portions of the slots of each pair extending toward each other.

5. As a new article of manufacture, a semaphore blade constructed entirely of a single sheet of metal having an unbroken face free from protruding fastening parts and formed with a pair of edge reinforcing flanges extending throughout substantially the entire length of the blade, and one or more intermediate flanges extending throughout a portion only of the length of the blade.

6. In a semaphore, a blade having later-

ally extending flanges at one end formed with slots, a metallic channel member having openings aligned with said slots and bolts passed through said slots, and said 5 openings, and having heads substantially fitting said channel.

7. In a semaphore, a blade having laterally extending flanges at one end formed with slots, a metallic channel member having 10 openings aligned with said slots and bolts

passed through said slots, and said openings, having heads substantially fitting said channel, and said blade formed with a plurality of longitudinal stiffening corrugations.

In witness whereof I have hereunto set my ¹⁵ hand this 31st day of May, 1921.

WILLIAM F. BOSSERT.
